Specification for Design.

Patented May 9, 1922.

Application filed September 1, 1921. Serial No. 497,716. Term of patent 14 years.

To all whom it may concern:

Be it known that I, ALFRED GERBENSKY, a citizen of the United States, residing at Okauchee, in the county of Waukesha and State of Wisconsin, have invented a new, original, and ornamental Design for a Toy, of which the following is a specification, reference being had to the accompanying drawing, forming part thereof.

I claim:

The ornamental design for a toy as shown and described.

In testimony that I claim the foregoing I have hereunto set my hand at Okauchee, in the county of Waukesha and State of Wisconsin.

ALFRED GERBENSKY.
